UNITED STATES PATENT OFFICE

RALPH F. MANNING, OF MEDFORD, MASSACHUSETTS

DESIGN FOR A TABLE ORNAMENT

Application filed November 29, 1932. Serial No. 46,197. Term of patent 14 years.

To all whom it may concern:

Be it known that I, RALPH F. MANNING, a citizen of the United States, residing at Medford, in the county of Middlesex and State of Massachusetts, have invented a new, original, and ornamental Design for a Table Ornament, of which the following is a specification, reference being had to the accompanying drawing, forming part thereof, of which

The wording shown by Figure 1 is regarded as forming a part of the design.

I claim:

The ornamental design for a table ornament as shown and described.

RALPH F. MANNING.
